UNITED STATES PATENT OFFICE.

WILLIAM A. GEIGER, OF CHICAGO, ILLINOIS, ASSIGNOR TO WILLIAM H. MINER, OF CHAZY, NEW YORK.

ANTIFRICTION BEARING.

1,405,681.

Specification of Letters Patent.

Patented Feb. 7, 1922.

Application filed May 7, 1921. Serial No. 467,522.

To all whom it may concern:

Be it known that I, WILLIAM A. GEIGER, a citizen of the United States, residing at Chicago, in the county of Cook and State 5 of Illinois, have invented a certain new and useful Improvement in Antifriction Bearings, of which the following is a full, clear, concise, and exact description, reference being had to the accompanying drawings, 10 forming a part of this specification.

This invention relates to improvements in anti-friction bearings.

The object of the invention is to provide a self-centering anti-friction bearing especially adapted for use as a side bearing on railway cars, the bearing being so formed that it is preferably attached to the under side of a body bolster or like member.

In the drawing forming a part of this 20 specification, Figure 1 is a vertical, sectional view taken lengthwise of a car through the body and truck bolsters thereof and illustrating my improvements in connection therewith. Figure 2 is a vertical, sectional 25 view taken lengthwise of the bolsters and corresponding substantially to the line 2—2 of Figure 1. Figure 3 is a top plan view of the bearing illustrated in Figure 1, parts being broken away in order to accommodate 30 the figure on the sheet. And Figure 4 is a detail, sectional view illustrating an alternate method of securing the wear plate and filler block rigidly together, as hereinafter described.

35 Referring first to the construction illustrated in Figures 1 to 3 inclusive, 10 denotes the upper bearing surface of a truck bolster and 11 the under side of an opposed body bolster. The improved bearing is adapted 40 to be attached to the body bolster and, as shown, said bear comprises, broadly, a retaining member or housing A; an anti-friction element proper B; a wear plate C; and a filler block D.

45 The retaining member A, as shown, is preferably in the form of a malleable casting having an upper flat surface and laterally extended perforated flanges 12 by which it is adapted to be secured to the body bolster 50 as by rivets 13. Said member A is provided also with downwardly extending vertical side flanges 14—14, horizontal walls 15—15 and vertical end flanges 16—16. The side walls 14, on their inner faces, are provided 55 with grooves, each groove having a vertical

entrance 17 merging into a horizontally extending portion 18, for the purpose herein-after described. It will be noted that the entrance 17 of each groove is offset from the center as clearly shown in Figure 1. 60

The anti-friction element B is in the form of a rocker of the gravity type having an upper cylindrical bearing surface 19 and a lower cylindrical bearing surface 20, said surfaces being concentric but the upper surface being struck on a shorter radius than the lower surface. Flat sides 21—21 are formed on the rocker, the same being arranged substantially tangential to the bearing surface 19. Said flat surfaces 21 are 70 adapted to engage with the under faces of the horizontal walls 15 of the member A to limit the rolling movements of the rocker B, as shown by the dotted position B' of the rocker in Figure 1. At its ends, the 75 rocker B is provided with laterally extended cylindrical studs 22—22 in axial alignment with the common center or axis of the two bearing surfaces 19 and 20. Said lugs 22, which function as journals for the rocker 80 B during the return of the latter to normal position after each actuation, extend within said grooves and are entered therein first vertically through the entrance portion 17 of the grooves and then slipped over horizontally 85 to a position in the center of the member A.

In the top portion thereof, the member A is cut out with a substantially rectangular opening as indicated at 23. Below the opening 23, the member A is provided with a widened recess as indicated at 24, said recess 24 being open at its ends as indicated at 24a—24a in Figure 2. The wear plate C, which may be of any suitable hardened material, is of generally rectangular form and is adapted to be slipped into position through the openings 24a in a direction transverse of the member A. The plate C is centrally perforated with two openings, 90 as shown, at 25—25 which come in the center of the member A when the plate C is in proper position.

The insert or filler block D, preferably in the form of a malleable casting, occupies 105 the rectangular opening 23 and is formed with a pair of depending cylindrical lugs 27—27, each having a rounded lower end as indicated at 28, said lugs 27 extending through the openings 25 in the plate C and 110

having the rounded ends 28 thereof depending below said plate C. Said depending ends 28 operate in the nature of teeth in co-operation with corresponding recesses 29—29 provided in the bearing surface 19 of the rocker B. With this construction, it is evident that the rocker B can never pass wholly out of engagement from both lugs 27 at the same time and consequently the 5 rocker B is prevented from bodily shifting with respect to the retaining member A and positive means are provided for maintaining the element B in central position when free from pressure.

10 The plate C and insert block D are held rigidly together by any suitable means such as the rivets 30—30 which are countersunk at both ends to lie flush with the corresponding outer surfaces of the block D and 15 plate C.

In assembling the bearing as shown, the rocker B is introduced within the member A as hereinbefore described. The plate C is then inserted transversely of the member 20 A and then the block D is applied vertically through the top of the member A. It is obvious that the plate C cannot shift in any direction in a horizontal plane after the block D is engaged therewith. By rigidly 25 uniting the block D and plates C as by the rivets 30, it then becomes impossible for the block D to be withdrawn vertically or the plate C to fall downwardly and the plate C is prevented from upward movement by the overhanging shoulders 31—31 30 in the member A. After the introduction of the block D with its projecting lugs 27 in engagement with the rocker B, the latter cannot be disassembled from the retaining 35 member A for the reason that the rocker B must always be in engagement with at least one of the lugs 27 and hence the studs 22 can never thereafter reach a position in vertical alinement with the entrance opening 40 45 17 of the guide grooves.

In actual practice, the diameters of the lugs 22 will be made slightly less than the vertical height of the horizontally extending portions 18 of the grooves in the member A 50 and a slight clearance normally left between the upper bearing surface 19 and the under face of the bearing plate C. In operation, when pressure is applied to the rocker element B, it will have its upper surface 55 engaged with the bearing plate C and the rocker will roll to either side of normal position—as for instance to the position B' shown in Figure 1. During this rolling movement of the rocker B, it is evident that 60 the studs 22 will travel in a straight line so long as the rolling action remains on the cylindrical surface 19. Upon removal of the pressure from the rocker B, the latter is 65 adapted to fall slightly so that the load is sustained by the studs 22 and, as the rocker

swings under the influence of gravity around said studs 22 as centers, the rocker will be automatically returned to its normal central position by reason of the inter-engagement of the lugs 27 and rocker B. 70

With the arrangement shown, the bearing may be manufactured at comparatively small expense and, when once properly assembled, may be shipped without danger of loss of parts or tampering therewith except 75 the parts are mutilated or destroyed. The rocker is self-centering under the influence of gravity and without the aid of any springs and may be designed to provide any necessary travel within the limits required 80 in railroad practice. By making the block D of a thickness such as to fully occupy the space between the top face of the plate C and the under face of the body bolster 11, the plate C is relieved of bending stresses 85 and is subject only to compression stresses as is also the block D.

Referring to the construction illustrated in Figure 4, I have shown a different method of securing the filler block D' with 90 the wear or bearing plate C'. This method consists in providing a vertical opening 130 in the block D' and an inclined opening 131 in the plate C' and then driving a friction pin 32 within said openings, the pin 32 being initially straight so that, as it is driven home, it is distorted in passing into the opening 131 and will remain in place so as to prevent either vertical separation of the members C' and D' or lateral shifting of one 100 with respect to the other. It will also be appreciated by those skilled in the art that the two openings 130 and 131 may be made both straight and an initially deformed pin driven into them with the same result. 105

I have herein shown and described what I now consider the preferred manner of carrying out the invention, but the same is merely illustrative and I contemplate all changes and modifications that come within 110 the scope of the claims appended hereto.

I claim:

1. In an anti-friction bearing of the character described, the combination with a retaining member adapted to be secured to the under side of a body bolster or the like; of an anti-friction gravity self-centering rocker element having supporting studs projecting from the ends thereof, the said member having grooves within which said studs 115 extend and provide supporting ledges for the studs; of a separate bearing plate inserted within said member above the rocker and on which the rocker is adapted to roll; a filler block within said member above said plate, said filler block having lugs projecting through said plate and cooperating with corresponding recesses in said rocker to maintain the proper relation of the rocker 120 with respect to said member; and means for 125 130

rigidly securing said block and plate together.

2. In an anti-friction bearing of the character described, the combination with a retaining member adapted to be secured to the under side of a body bolster or the like, said retaining member having an opening in the top thereof and transversely extending openings, said member having also depending side walls formed on the inner sides thereof with supporting horizontally extending ledges; of a rocker having supporting studs extending from the ends thereof, said studs being supported on said ledges; a bearing plate insertible through said transversely extending openings above said rocker and forming the upper bearing for the latter, said plate having a vertical opening therethrough, a filler block insertible vertically through said opening in the top of said member to substantially occupy said opening, said block having a lug depending from the bottom thereof and extending through said opening in the bearing plate, said rocker having a recess cooperable with said depending lug; and means for rigidly securing said filler block and bearing plate together.

3. In an anti-friction bearing of the character described, the combination with a retaining member adapted to be secured to the under side of a body bolster or the like, said retaining member having an opening in the top thereof and depending side walls, each of said side walls being provided on the inner side thereof with a groove having

a vertical entrance offset from the center of the retaining member and a horizontally extending section, the latter providing horizontally extending supporting ledges; of a gravity self-centering rocker having upper and lower concentric surfaces struck on different radii, the upper surface corresponding to the shorter radius, said rocker having supporting studs extended from the ends thereof in axial alinement with the common center of said bearing surfaces, said lugs projecting within said grooves and insertible in the latter through the entrance openings thereof, said lugs supporting the rocker from said horizontal ledges when the rocker is in operative position; a bearing plate insertible transversely of said member above the rocker and with which the upper surface thereof is adapted to engage, said plate being provided with vertically extending openings; a filler block insertible vertically within the opening in the top of said retaining member, said block having depending centering lugs extending through said openings in the bearing plate and below the latter, said rocker having recesses cooperating with said lugs; and means for rigidly uniting said filler block and the bearing plate.

In witness that I claim the foregoing I have hereunto subscribed my name this 5th day of May, 1921.

WILLIAM A. GEIGER.
